UNITED STATES PATENT OFFICE.

FRANCIS W. BRADY, OF ENGLEWOOD, NEW JERSEY.

VALVE-GEAR FOR INTERNAL-COMBUSTION ENGINES.

No. 860,630.

Specification of Letters Patent.

Patented July 23, 1907.

Application filed March 2, 1905. Serial No. 248,003.

To all whom it may concern:

Be it known that I, FRANCIS W. BRADY, a citizen of the United States, residing at Englewood, in the county of Bergen and State of New Jersey, have invented certain new and useful Improvements in Valve-Gear for Internal-Combustion Engines, of which the following is a full, clear, and exact specification.

My invention relates to certain new and useful improvements in internal combustion engines and the object is to provide an engine which may be satisfactorily operated with the various grades of liquid fuel, including the heavier oils and which shall be economical in operation, simple in construction and efficient.

To this end my invention consists of the combinations and parts hereinafter more particularly referred to and which includes novel means for vaporizing the fuel within the engine proper and at a comparatively high temperature, the provision of a special fuel receiver which is constantly subjected to a strong current of air during the feeding of the fuel for the purpose of more efficiently vaporizing it, and the provision of means whereby the fuel receiver is swept clean after each explosion and before a new charge of fuel is inserted.

A further improvement consists in novel means for injecting the proper amount of fuel at the proper time and the delivering of it to the fuel receiver, and there are other numerous improvements and advantages which will be pointed out more particularly hereafter.

In the accompanying drawings forming part of my application I have illustrated one form of my invention but I do not wish to be understood as limiting myself to the particular arrangement of parts therein shown, as many modifications and changes can be made therewithout departing from the spirit of my invention. In these drawings Figure 1 is a sectional elevation showing the parts in detail, and as I prefer to arrange them. Fig. 2 is an enlarged cross-sectional view taken on line $x-x$, Fig. 1, of the pilot or main valve showing the fuel feeding port and coating mechanism. Fig. 3 is a similar view to Fig. 2 but shows the parts in different relative positions, while Fig. 4 is a plan view of the cycle controlling or operating cam, and shows diagrammatically the several operations as they occur during the working of the engine.

In these drawings, 1, represents the shell or casing of the engine cylinder, a water jacket 2, of ordinary form, being provided as shown. Within the cylinder the piston 3 is adapted to move, the connecting rod 4 being secured to the cross head 5 and thus with the main crank shaft 6 in the usual manner. At the upper end of the engine cylinder is provided a combustion or explosion chamber, 7, having a vaporizing portion or compartment 8. A partition or pilot valve 9, is adapted to close the aperture connecting the combustion and vaporizing chambers at certain periods during the

operation of the engine. This pilot valve is mounted upon the stem 10 within a suitable stuffing box 11, in the head of the cylinder, and the valve is normally maintained in a closed position by means of a spring 12. It is opened by the action of a tappet lever 13, fulcrumed at any suitable point as at 14, and one end of which lever carries a friction roller, 15, which contacts with a cam 16, connected to and operated by suitable gearing from the main shaft 6, as will hereafter be more particularly described. In the explosion chamber is located any desirable sparking or exploding device such as the electrically operated device shown, wherein there is provided an electric circuit, in which are located sparking terminals 17 and 18, across which an electric spark is adapted to jump at the proper time. The construction and operation of this device is similar to those now in use and well understood, and as it forms no part of my present invention need not be more particularly described.

In Fig. 1, 19, indicates the air inlet pipe having a port governed by a valve 20, which is normally maintained closed by the spring 21. A valve 22 governs the exhaust port 23 and is normally held in place by gravity, or by some spring mechanism as may be desired. Fuel is supplied to the engine through the pipe 24, channel 25, and to the recess or compartment 26, located adjacent to and surrounding the pilot valve stem (see Figs. 2 and 3), which stem is provided with longitudinal recesses or grooves 27 of sufficient extent to permit the flow of the required quantity of fuel to the vaporizing chamber upon the full depression of the stem.

The operation of the device will now be described, and it will best be understood in connection with the diagrammatical representations shown in Fig. 4. Assuming that an explosion has just taken place, the piston is driven downwardly thereby. The cam, rotating in a clockwise manner as shown in Fig. 1, is so disposed that when the piston has very nearly reached the end of its down stroke, the portion a contacts with the tappet lever, the stem 10, is depressed and the pilot valve 9 opens communication between the combustion chamber and the vaporizing chamber. The return stroke of the piston drives from the combustion and vaporizing chambers the exhaust and unused vapors, the friction roller 15 having a dwell upon the cam 16 between a and a point short of b . During the upward stroke of the piston the valve 22 lifts and is held open by the pressure for this purpose. Upon the beginning of the next downward stroke the valve 22 closes by reason of its gravity and the release from pressure and the valve 20 opens because of the vacuum created by the piston in its downward movement. At this point, therefore, a current of air is drawn in through pipe 19, and, flowing past the pilot valve or partition 9, sweeps it clean of products of combustion which may have been deposited thereon. While this current of air is flowing and

the piston moving downward, a further movement of the pilot valve and stem is caused by the projection *c* on the cam 16, contacting with the tappet arm friction roller, and this further depresses the stem 10 to a sufficient extent to permit the necessary quantity of fuel to be sprayed down along said stem and directly upon the pilot valve 9, which then acts as a fuel receiver, and, becoming very highly heated during the working of the engine, serves as a very efficient aid in the vaporization of the fuel injected. During the fuel feeding operation the current of air is still flowing directly upon the fuel and fuel receiver and aids in vaporizing the same, and the engine stroke and cam gearing is so arranged that the current of air continues to flow upon the fuel receiver after the fuel supply has been cut off, when the roller rides off of the elevation *c* on the cam. Thus all of the fuel is properly vaporized and no waste or refuse is permitted to remain on the receiver. By the time the piston has started upon its next return stroke the roller 20 on the tappet arm rides off of the portion *d* of the cam and the pilot valve 9, closes so that the continued upward stroke of the piston compresses the charge in the combustion chamber until it is ignited and exploded, at or about the time the piston has reached its extreme 25 position. After the explosion the above described operation is repeated as before.

In the apparatus here illustrated I have shown the air inlet and exhaust ports operated automatically, and this is a preferable arrangement as thereby all danger of 30 a back fire into the inlet pipe, in the event of the firing of a charge in the cylinder when the air valve is open is obviated. If the valve were positively held open in such a case, the fire would strike back, but if it is automatically operated as shown, the combustion will cause 35 sufficient pressure to close the valve and the gases will pass to the exhaust as described.

Any means of feeding the liquid fuel to the engine may be employed, such as gravity or pressure but in using the heavier petroleum products, a pressure feeding apparatus of some sort will be found most satisfactory. I have shown the exhaust port opening into what I have termed a vaporizing compartment or 40 chamber but this is not a necessary arrangement and it may be located in direct communication with the combustion chamber. By so doing the small portion of unexploded mixture which is left in the vaporizing chamber upon closing the pilot valve would not be discharged into the air with the exhaust, but would be retained there for injection into the explosion chamber 45 with the feeding of a new charge.

Various other modifications and changes may be made in my apparatus without departing from the spirit of my invention and I do not limit myself to the particular arrangements shown and described, but 50

55 What I claim and desire to secure by Letters Patent is:

1. In an internal combustion engine, a combustion chamber, an air inlet valve communicating with the combustion chamber and provided with a vaporizing surface, and means for feeding a liquid hydrocarbon directly onto the vaporizing surface of said valve during part only of the suction stroke.

2. In an internal combustion engine, a combustion chamber, a vaporizer communicating therewith and having a vaporizing surface, means for drawing air through

the vaporizer into the combustion chamber throughout the suction stroke of the engine, and means for feeding a liquid hydrocarbon directly onto the vaporizing surface during a part only of the suction stroke.

3. In an internal combustion engine, a combustion chamber, an air inlet therefor, a vaporizing surface in the path of the incoming air, and means for feeding a liquid hydrocarbon directly onto the vaporizing surface during a part only of the suction stroke.

4. In an internal combustion engine, a vaporizer having a vaporizing surface, means for feeding the liquid to be vaporized directly onto said surface at intervals, and means for directing a current of air against said surface after the feed of the liquid has stopped.

5. In an internal combustion engine, a vaporizer having a vaporizing surface, means for feeding the liquid to be vaporized directly onto said surface at intervals, and means for directing a current of air against said surface during the feed of the liquid and after the feed of the liquid has stopped.

6. In an internal combustion engine, a chamber through which the products of combustion are exhausted, a vaporizing surface in said chamber, means for feeding liquid fuel directly onto said vaporizing surface at intervals, and means for sweeping the products of combustion off of said vaporizing surface after the exhaust and before the fuel feed.

7. In an internal combustion engine, a combustion chamber through which the products of combustion are exhausted, a vaporizing surface in the path of the exhaust gases, means for feeding a quantity of liquid fuel directly onto said surface at intervals, and means for passing a current of air across said surface and into the combustion chamber.

8. In an internal combustion engine, a combustion chamber, a vaporizing chamber communicating therewith, air inlet and exhaust ports in said vaporizing chamber, a puppet valve between the combustion and vaporizing chambers, a stem for said valve, a casing surrounding said stem, an oil reservoir between the stem and casing, and oil ducts in the stem so constructed and arranged as to open communication between the reservoir and vaporizing chamber and feed oil directly onto the surface of the valve when the puppet valve is open.

9. In an internal combustion engine, a combustion chamber, a vaporizing chamber communicating therewith, air inlet and exhaust ports in the vaporizing chamber, a puppet valve between the vaporizing and combustion chambers, a stem for said valve, a casing surrounding said stem, an oil reservoir between the stem and casing, oil ducts in the stem, and means for imparting a plurality of distinct movements to said stem in one direction, said stem, ducts and casing being so constructed and arranged that after one movement of the stem the puppet valve is open and the ducts are closed by the casing, and upon a subsequent movement of the stem the ducts are opened to feed oil from the reservoir onto the surface of the puppet valve.

10. In an internal combustion engine, a combustion chamber, a vaporizing chamber communicating therewith, air inlet and exhaust ports in the vaporizing chamber, a vaporizing surface in said vaporizing chamber and in the path of the exhaust gases, a puppet valve between the combustion and vaporizing chambers, a stem for said valve, a casing surrounding said stem, an oil reservoir between the stem and casing, oil ducts in the stem, and means for imparting a plurality of distinct movements to said stem in one direction, said stem, ducts and casing being so constructed and arranged that after one movement of the stem the puppet valve is open and the ducts are closed by the casing, and upon a subsequent movement of the stem the ducts are opened to feed oil directly onto the vaporizing surface.

In testimony whereof I have hereunto set my hand in the presence of two subscribing witnesses.

FRANCIS W. BRADY.
